SHEET-METAL FIRE-RESISTING CLOSURE.

1,139,842.

Specification of Letters Patent. Patented May 18, 1915.

Application filed August 22, 1908. Serial No. 449,819.

To all whom it may concern:

Be it known that we, JOAH BROGDEN and JOHN W. WATKINS, of Philadelphia, in the county of Philadelphia and State of Pennsylvania, have invented certain new and useful Improvements in Sheet-Metal Fire-Resisting Closures, of which the following is a specification, reference being had to the accompanying drawings.

- 19 In any considerable superficial area of a closure is made of an integral piece of metal the entire sheet of metal bends or warps when attacked by fire, and thereby the fire resisting capacity of the closure is destroyed.
- 15 We have discovered that it is possible to form a closure by so combining a series of sheet metal parts presenting comparatively small superficial areas as to practically overcome this injurious tendency of the closure to warp. This is due to the different action under the influence of heat of a solid metallic sheet as compared with a sectional one. In the former whatever bend or set one part takes from the heat is communicated to and 25 reproduced in all parts, so that its edges may be warped many inches out of true. But a sectional sheet of the same size, if properly constructed according to our invention, will not so act, for the bending or warping 30 of one section is not communicated to adjoining sections, each of which warps, if at all, quite independently of the others, and usually along different lines, so that although heat may corrugate or wrinkle the 35 surface of the sectional plate, it does not materially disalign the edges of the plate.

Our invention relates to a sheet metal closure containing no combustible material, and having its superficies so built up by the 40 union of a number of smaller sheet metal parts that under the influence of intense heat, the closure does not injuriously warp or bend. But, in order to accomplish the 45 end of our invention, it is essential that the adjoining edges of these smaller sheets, should be so interlocked, as that the multiplication of joints which is occasioned by the multiplication of parts shall not destroy the fire resisting properties of the closure, 50 by affording joints through which the fire

may find its way. And for this reason it is essential to our invention that the component sheets are not merely overlapped or riveted together, since, under the influence of intense heat, such joints readily part and 55 permit the fire to pass with unbuckling of the rivets. Accordingly, in our invention, the abutting edges of the discontinuous sheets are to be united or interlocked by a continuous interfolding of the edges, whereby one edge is received within the folds of the other, and both edges turned in from the external surface of the closure. Such a closure may be employed to close a door, window or other opening through which it 60 is desired that a fire, whether occurring within or without the building, shall not pass.

We have illustrated our invention as applied to a sliding fire door, but it will be 70 understood that the scope of the invention is not thus limited.

In the accompanying drawings, Figure I, is a front elevation of a sliding fire door embodying our invention. Fig. II, is a vertical 75 cross section along the line II, II, of Fig. I. Fig. III, is a similar section along the line III, III, of Fig. I. Fig. IV, is a broken horizontal section along the line IV, IV, of Fig. I, and Fig. V, is a sectional view illustrating the construction of one of the laminated strengthening plates inserted at the edges of the structure as hereinafter explained.

Referring to Fig. I, the door 1, is provided with metal straps 2, 2, in which pulleys are journaled running on the bar or track 3, in appropriate relation to the top of the aperture 4, to permit the door to be run along the track to close or open it. A 80 catch 5, stops the door when it has been slid to the closing position, and a roller 6, holds the lower corner of the door in place.

The door itself is formed wholly of non-combustible material, and as herein shown, 95 consists of separated faces which are built up by combining a number of horizontal metal strips or pieces 10, 10, of comparatively small superficial area. The pieces are connected solely by infolding, and then in- 100

terlocking the infolded adjacent edges of the pieces. The folds on one face are preferably turned up, and on the other face turned down, thereby slightly staggering the same.

5 This interlocking of the edges forms folds 11, 11, on the inner sides of the faces, as clearly shown in Figs. II and III.

The metal pieces are of sufficient weight and strength so as to be self-sustaining.

10 That is, these interlocked metal pieces will without the use of the objectionable central wooden core, or the objectionable strengthening bolts running through the entire door, form a substantially rigid door body. The 15 interlocked joints between the metal pieces also serve as the sole means for connecting said metal pieces.

The two uppermost facing strips are united over the top by a centrally depressed 20 top piece 12, provided with upwardly extending walls 13, resting between the top facing strips, and having their upper edges interlocked by folds 14, with the upper edges of the facing strips. In this way the top is 25 depressed below the upper edge, the space thus afforded permitting the door to be hung in such relation to the track 3, that its edges rise slightly above the lower edge of the track, so that in case the straps 2, 2, 30 should give way, the closure would still be held against the aperture by the engagement of these edges with the track.

The bottom of the door is formed by a similar centrally elevated bottom piece 15, 35 provided with downwardly extending walls 16, resting between the lowermost facing strips, and having their lower edges interlocked by folds 17, with the lower edges of the facing strips, thus forming an arched 40 bottom which is useful as a flame trap, preventing a slight flame from creeping directly beneath the door.

The sides of the door are formed of side-pieces 26, having their edges interlocked by 45 folds 27, with the ends of the facing strips.

For the more effectual union and strengthening of the facing strips they are interiorly braced by vertical partitions as follows:— To the inner side of each face of the closure 50 are riveted vertical flange strips 18, bent to provide one portion for riveting to the facing strips, and another portion which is folded as seen in Fig. IV. The flange strips on the opposite facings correspond with each 55 other, and each pair are united by a union 20, the folded edges of which interlock with and thus unite the folded edges of the two flange pieces 18, as seen in the drawing. These unions 20, may be slid into place ver- 60 tically after the faces of the door are otherwise fully assembled. The vertical flange strips 18, are riveted to the horizontal fac- 65 ing strips by rivets which pass through the thickened parts of the structure occasioned by the double folded interlocks 11, whereby

the rivets serve the double function of firmly securing the interlock and also securing the flange strips in place.

It will be observed that the vertical partitions thus formed by combining the flange 70 strips and the unions are composite in their nature, each formed by the interfolding of a plurality of sheet metal parts with their major surfaces at right angles to the outer surface of the closure, consequently afford- 75 ing a maximum resistance against warping of the surface of the closure. An integral bolt or rod running vertically through the structure would tend to bend or warp under heat. But a composite partition made of 80 sheets running cross-wise to the thickness of the closure does not have such tendency.

The number of partitions depends upon the extent to which it is desired to strengthen the door. We prefer to place one partition 85 in immediate proximity to each edge of the door, leaving sufficient space beyond them and the side pieces to permit the slipping in of a laminated strengthening piece 22, the structure of which is shown in cross section 90 in Fig. V, being built up of three pieces of sheet metal, the two lower pieces 23, 23, as seen in the drawings being narrower strips, while the upper one 24, is of greater width and has its edges bent around and under to unite 95 all three strips together. A laminated strip of this construction and thus placed athwart the plane of the door has great resistance to torsional or warping strains, and by being placed along either edge of the door greatly 100 reinforces its power of resistance to forces tending to disturb the alignment of the edges of the door.

A closure constructed as has thus been de- 105 scribed acts quite differently under the influence of heat from one having any considerable superficial area composed of a single sheet. It does not warp as a whole and therefore its edges remain in alignment and effectually close whatever aperture it is 110 applied to, notwithstanding such harmless wrinkling or corrugation of the individual plates as may occur. At the same time the strengthening partitions and the laminated bars are so applied as to offer great resist- 115 ance to torsional or warping strains.

We are aware that it is not new to make a so-called fire-proof closure of wooden parts each separately sheathed with metal and then united. Such a closure is entirely 120 different from our invention, not only be- 125 cause our closure employs no combustible material, but because wood so sheathed is subject to destructive distillation under the influence of high temperatures, generating gaseous pressure which causes the bursting of the metallic sheath and the complete de- destruction of the closure.

We are also aware of hollow sheet metal composite structures constructed for card- 130

barracks as illustrated in United States Letters Patent No. 376,979, to De La Sausse, dated January 24th, 1888, but, in these structures the edges of the sheets have been 5 united by overlapping and riveting, or by simple overlapping, without that infolding and interfolding of the sheets which is essential in a structure which is designed especially as a fire resisting closure, adapted to 10 maintain a fire joint under the intense heat of conflagration.

We are also aware that fire shields, so called, have been made of sectional parts in order that they may be readily carried about 15 and quickly assembled, but this bears no relation to our invention, since fire shields are not intended to close an aperture and therefore the question of the maintenance of the alinement of their edges is not of im- 20 portance.

Our invention relates solely to closures, by which we mean a structure of considerable area intended to close an aperture against fire by the maintenance of close 25 contact between the edges of the closure and the edges surrounding the aperture.

It will also be understood that our structure is differentiated from the wooden structures, to which reference is made, by 30 the absence of combustible material, which distinction will be pointed out in the claims by the use of the phrase "a non-combustible sheet metal closure." If desired the hollow parts of our closure may be rendered 35 slightly more non-conductive of heat by the insertion of rolls of asbestos paper or other non-heat conducting and fire resisting materials, but such materials are non-combustible and therefore excluded by the distinc- 40 tive term which we shall employ in the claims.

Having thus described our invention, we claim:—

1. In a fire resisting closure in combination sheet metal non-integral surfaces, and composite partitions uniting the same at intervals, formed by the interlocking of a union with two corresponding flange pieces affixed one to each surface.
2. A hollow fire-resisting closure formed wholly of non-combustible material and consisting of separated faces, each of which is composed of a number of sheet metal pieces of comparatively small superficial 55 area of sufficient weight and strength to be self-sustaining, said pieces being connected together by the infolding and interfolding of the adjacent edges of said pieces, and composite partitions formed by interfolding sheet metal parts, said partitions being fastened to the metal pieces forming the faces by rivets which pass through the interfolded edges of said pieces.
3. A hollow fire-resisting closure formed

wholly of non-combustible material and 65 consisting of separated faces, each of which is composed of a number of self-sustaining sheet metal pieces of comparatively small superficial area, said pieces being connected together by the infolding and interfolding 70 of the adjacent edges of said pieces and partitions extending at an angle to the interlocked edges of said metal pieces, across said interlocked edges, and riveted thereto.

4. A door comprising a hollow body, two 75 partition spacing members secured respectively to opposite inner sides of the body, intermediate of opposite edges of the body each spacing member having a lateral flange which abuts against the flange of the other 80 spacing member, each flange having a portion turned toward the side of the body to which the member is secured, and a channel member having inwardly turned flanges which embrace the flanges of said spacing 85 members and hold said members from relative lateral movement and from movement away from each other.

5. A door comprising a hollow body, two partition spacing members of channel form 90 having their outer flanges secured respectively to opposite inner sides of the body intermediate of opposite edges of the body, and a member having interlocking engagement with the inner flanges of said members 95 for holding them from relative lateral movement and from movement away from each other.

6. A door comprising a hollow body, two partition spacing members of channel form 100 having their outer flanges secured respectively to opposite inner sides of the body intermediate of opposite edges of the body and their inner flanges abutting against each other, and a member having interlocking engagement with the inner flanges of 105 said members for holding them from lateral relative movement and from movement away from each other.

7. A door comprising a hollow body, two 110 partition channel spacing members having their outer flanges secured respectively to opposite inner sides of the body intermediate of opposite edges of the body and each member having its inner flange provided 115 with a portion projecting toward the outer flange of said member, and a channel member having inwardly turned flanges embracing the inwardly turned portions of the inner flanges of the spacing members.

8. A door comprising a hollow body, two partition channel members secured respectively to opposite inner sides of the body, intermediate of opposite edges of the body, the inner flanges of said members being disposed parallel with and abutting against each other, each of said inner flanges having a portion projecting toward the outer

flange of said member, and a channel member having inwardly turned flanges respectively embracing said projecting portions of the inner flanges, for holding the said two channel members from relative lateral movement and from movement away from each other.

In testimony whereof, we have hereunto

signed our names at Philadelphia, Pennsylvania, this twenty-first day of August 1908.
